UNITED STATES PATENT OFFICE.

AMBROSE S. CARNELL, OF NEW YORK, N. Y.

VENDING-MACHINE.

1,054,671.

Specification of Letters Patent.

Patented Mar. 4, 1913.

Application filed March 25, 1909. Serial No. 485,609.

To all whom it may concern:

Be it known that I, AMBROSE S. CARNELL, of New York, in the county of New York, and in the State of New York, have invented 5 a certain new and useful Improvement in Vending-Machines, and do hereby declare that the following is a full, clear, and exact description thereof.

More especially, my invention relates to 10 an improvement in newspaper vending machines or vending machines adapted to dispense periodical literature, maps, pictures, prints, etc., and other articles.

The object of my invention is to provide 15 a device of this character which is very simple in construction and which is, nevertheless, positive in operation and free from any liability to get out of order.

A further object of my invention is to 20 provide a vending machine which is so constructed that it can be filled with newspapers, periodicals, maps, pictures, prints, etc., of any thickness, and having a wide range in size and shape as to their other dimensions, without the necessity of adjustment or interchangeable parts.

A further object of my invention is to 25 provide a vending machine so constructed that the article to be dispensed is largely or wholly in view.

My vending machine is, furthermore, adapted to be operated by the insertion of any one of a variety of different coins, the mechanism being adjustable so as to receive 35 and be operated by one or a number of coins previously determined.

I have shown my invention in the accompanying drawings, in which—

Figure 1 is a vertical cross-section of the 40 machine; Fig. 2 is a vertical cross-section of the upper portion of the same, the section in this figure being taken at right angles to that in Fig. 1; Fig. 3 is a vertical cross-section of the entire machine partly in elevation, taken in the same plane as Fig. 2; Fig. 4 is a horizontal cross-section taken 45 through the top of the machine; Fig. 5 is a similar section showing certain of the parts enlarged; Fig. 6 is a vertical cross-section 50 showing certain of the parts enlarged, taken in the same plane as Fig. 1; Fig. 7 is a vertical cross-section taken in the same plane as Fig. 3, and showing certain of the parts enlarged; Fig. 8 is a horizontal cross-section 55 of another modification of my invention;

tion; Fig. 9 is a similar section showing the parts enlarged; Fig. 10 is an elevation of one of the winding drums shown in Figs. 8 and 9; and Figs. 11 and 12 are plan views of certain details enlarged.

In the modification shown in Figs. 1 to 7, 60 Fig. 1 is a box-like casing having a window 2 at the front thereof and a lid 3 upon its top. The casing 1 is also provided at one of its lower edges with a discharge spout 4 for 65 the newspapers. The spout 4 has a flange 5 at its outer end to retain a paper discharged into the same until removed.

As best shown in Figs. 6 and 7, a shaft 6 projects through one side of the casing and 70 carries a crank 7 for operating the same. The inner end of the shaft 6 is supported in journal bearings attached to a bracket 9 riveted to the interior of the casing 1. Keyed to the shaft 6 there is a wheel 10 75 having a slot 11 therein. To the wheel is attached a bracket 12, to be hereinafter referred to. Upon the periphery of the wheel 10 there is situated a sprocket wheel 13 having two short diametrically opposed slots 14, 80 adapted to register with the slot 11. The sprocket wheel 13 carries a plurality of sprocket teeth 15 upon its periphery, and also at one side of the sprocket teeth two diametrically opposed notches 16. A pawl 85 17 is pivoted to the casing 1, and designed to ride upon the portion of the wheel 13 carrying the notches 16. The pawl 17 has a weighted arm 18 attached thereto to normally withdraw the pawl from engagement with the notches 16. When the lid 3 is closed, a spring 19 carried by a pin 20, supported by a base 21 upon the lid 3, 90 presses upon the upper side of the pawl 17 so as to bring the pawl into engagement with the notches 16. The side of the sprocket wheel 13 carries two diametrically opposed pins 22, which are adapted to be engaged by a sliding bar 23 supported in 95 guide-ways 24 upon the bracket 12. The innermost end of the slide bar 23 is provided with a right-angle projection 25, which is designed to ride within a cam groove 26 located in a stationary cam bracket 27 secured to the bracket 9. A coin chute 28 is adapted 100 to conduct coins into the grooves 11 and 14, when in their uppermost positions. The chute 28 is connected at its upper end with a housing 29 suspended from the top of the casing 1 and carrying a pivoted coin guide 110

30. The coin guide 30 is operated by means of a link 31 and mechanism attached thereto, to be hereinafter described. The coin guide 30 in one position registers with the upper 5 end of the coin chute 28, and in another position, with the top of a curved discharging chute 32, leading around the wheels 10 and 13 to a pocket 33, supported by and projecting outside of the casing 1.

10 The bracket 12 carries a longitudinal slot 34, which registers with the slot in the wheel 10. The slot 14 is of such a size as to prevent the passage of a five-cent piece therethrough. When, therefore, the machine is intended to be operated by five-cent pieces, 15 any smaller coin will pass entirely through the slot 14 into the slot 34, and thence into a chute 35 which connects with the pocket 33. Should it be desired to operate the 20 machine with pennies, a number of adjustable screws 36 may be provided to prevent the passage of the pennies into the chute 35. In case it is desired to operate the machine with a single penny, the adjustable 25 screw located nearest to the discharge end of the chute 28 is screwed up so as to close the slot 34. A penny when inserted under these circumstances will be stopped by the 30 said screw in the position ordinarily occupied by a five-cent piece.

Should it be desired to operate the machine with two pennies, the middle screw 36 is screwed up so as to close the slot 34, whereupon it is necessary that two pennies be 35 present in the machine before a coin will be retained within the slot 14 of the wheel 13. Again, the machine may be adjusted to operate by the presence of three pennies, by screwing up only the adjustable screw 40 36, shown to the left of Fig. 7. Under these circumstances, it will be seen that the presence of three pennies are required in order to retain one of the pennies within the groove 14 of the wheel 13.

45 Two stops 36' are provided so as to engage the crank 7 and prevent the same from rotating more than 180 degrees. The wheel 10 is thus capable of only a half revolution. In the position shown in Fig. 50 7, the wheel 10 and the wheel 13 are ready to receive a coin for operating the machine. After a coin has been inserted so as to be retained in the grooves 11 and 14, in order to operate the machine, the crank 7 is turned 55 a half revolution. The presence of the coin locks the sprocket wheel 13 to the shaft 6. As a consequence, upon the rotation of the 60 crank 7, both the groove 11 and the groove 14 are moved into a position directly beneath the shaft 6. In this position of the parts, the paper will have been discharged and the coin will now roll downwardly out of the groove 14 into a chute 37, leading to a 65 hopper 38 in the interior of the casing 1. A chute 39 having at its top a funnel 40 and

connecting at its bottom with the hopper 38, is also provided beneath the slot 34, so that in the lowermost position of said slot, any pennies present in the slot will be discharged into the funnel 40 and the hopper 70 38.

A sprocket chain 41 connects the sprocket wheel 13 to another sprocket wheel 42 situated upon a shaft 43 carrying a table 44. The shaft 43 carries an additional sprocket wheel 45 which is connected by means of a chain 46 to a sprocket wheel 47 and a sleeve 48 upon a shaft 49. The sleeve 48, which is carried loosely upon the shaft 49, is provided at one end with a number of teeth 50, 80 which are designed to engage with a series of similar teeth 51 situated upon a sleeve 52 keyed to the shaft 49. The sleeve 52 carries a housing 53 for a spring 54, designed to normally press outwardly a pin 85 55, to cause the latter to engage with a number of teeth 56 upon the inner periphery of a winding drum 57 loosely carried by the shaft 49. The sleeve 58 is keyed to the shaft at the other side of the winding drum 90 57, to prevent longitudinal movement of said drum. Another sleeve 59 and winding drum 60 is provided at the other end of the shaft 49 and constructed in the same manner as the sleeve 52 and drum 57, except for the omission of the clutch members. Each of the drums 57 and 60 has a slot 61 in its outer periphery to receive the knotted end 62 of a string, tape, cord, wire or substitutes therefor, and hereafter referred to 100 as string or cord 63, adapted to be wound around each of the drums. The strings 63 lead from the drums 57 and 60 to the table 44, around which they are wound. The remaining ends of the strings 63 are designed to be secured to the table 44 at one end 105 thereof within slots 64.

The sleeve 48 carries a groove 65 for receiving the bifurcated end 66 of a lever 67, pivoted at its center upon a bracket 68 attached to the inside of the casing 1. A spring 67' connects the lower end of the lever 67 with the casing 1, so as to normally disengage the clutch. The other end of the lever 67 has a beveled surface 69 designed to coöperate with a beveled lug 70 situated upon the under side of the lid 3.

The link 31, above referred to as attached to the coin guide 30, is connected at its other end to a bell-crank lever 71, pivoted at 72 110 to the casing 1. The other end of the bell-crank lever has a spring 73 attached thereto for normally maintaining the coin guide 30 in a vertical position. To the same end of the bell-crank lever there is also attached 115 a link 74 leading to a lever 75 pivoted at 76 to the casing and provided at its outer end with a slot 76'. One of the strings 63 is designed to pass through the slots 76', and the slot is made of such a width that it 120 125 130

would prevent the passage therethrough of a knot or obstruction 77, situated upon the said string 63.

When the lid 3 is raised, the upper end 78 of the lever 79 pivoted at 80 to the casing 1, is released so as to permit a spring 81, attached to the inside of the casing, to bring a brake-shoe 82 into contact with the periphery of each of the drums 57 and 60.

10 A table, consisting of a pair of fixed rods 83, attached to the sides of the casing 1 at the top thereof, is provided to support a bundle of newspapers when the lid is opened for re-charging the machine.

15 In the modification shown in Figs. 8 to 12, a removable table 84 is shown, the purpose being in this modification to permit the insertion into the machine of a table previously charged with a supply of newspapers, 20 so that the table can be provided with a supply of newspapers at a central plant, and the table thus charged conveyed to the machine and inserted at once without delay. In this modification, the table 84 has attached at the 25 middle of each side thereof, a slide bracket 85 having flanges 86 at the top thereof. The slide bracket 85 is adapted to be received within a slide-way 87, situated in a stub shaft 88 at each side of the machine.

30 As shown in Fig. 9, one of the stub shafts 88 is retained in place by means of a flange 89 located upon the outside of a journal bearing bracket 90, while the other stub shaft 88 is retained in place in a journal bracket 91 by means of a screw 92, registering with a groove 93 in said stub shaft. In order to retain the slide members 85 in position in the stub shafts 88, each of the latter carries a pivoted block 94 having a spring pressed pin 95 projecting through the top thereof and registering with a recess 96 in the top of the slide bracket.

As shown in Fig. 10, each of the drums 57 and 60 carries a slot 97 upon an edge thereof, 45 to receive the knotted end of the string. Each of the drums is, furthermore, provided with a slot 98 extending entirely through the periphery of the drum and connecting with a recess 99 in the body thereof.

50 In the operation of the device, assuming that the machine has been charged with a plurality of newspapers or other periodicals, the position of the table 44 will be such that the upper half of the front page of the newspaper carried by the table 44 will appear through the window 2 at the front of the machine. Upon the insertion of a proper coin into the coin guide 30, the same will direct the coin into the recesses 11 and 14, if 55 the latter are located at the upper ends of their paths. In case the recesses 11 and 14 are not in their proper positions, the crank 7 can be rotated to the left until it comes in contact with one of the stops 36', so as to bring said recesses into their proper positions.

Upon this movement of the crank 7, the slide bar 23 comes in contact with the stop 22 so as to rotate the shaft 6 and wheel 13 in unison. When the slots 11 and 14 are in this position, the machine cannot be operated, of course, until the coin has been inserted, which will extend above the slot 11 into the slot 14, so as to clamp the wheel 13 to the shaft 6. In case it is designed to operate the machine with five-cent pieces, upon the insertion of a five-cent piece, the latter projects into the slot 14 in the wheel 13 so as to clamp the latter to the shaft 6. When now the crank 7 is rotated to the right, the sprocket wheel 13 is turned with the shaft 6, thus conveying rotary motion to the table 44 and discharging a paper through the chute 4, where it is retained by the flange 5 until removed. When the machine is thus set for operation with five-cent pieces, in case any pennies should be inserted, the latter are conducted into the chute 35, where they are discharged into the pocket 33 at the outside of the machine. Should it be desired to operate the machine with a single penny, the set screw 36 nearest the end of the chute 28 is screwed up so as to close the slot 34. When so closed, a penny will extend upward into the slot 14 and clamp the wheel 13 to the shaft 6 in the manner above described. In case it is desired to operate the machine with two pennies, the middle screw 36 is screwed up so as to close the slot 34 at that point; and in case it is desired to operate the machine with three pennies, the adjustable screw 36 shown at the left of Fig. 7 is screwed up so as to close the slot at that point.

Upon the rotation of the crank 7, so as to operate the machine and effect the discharge of the newspaper, when the crank 7 reaches the end of its path, the various coins are discharged into the hopper 38. In case the machine has been operated by a five-cent piece, the latter is discharged into the hopper through the chute 37. The same is true when the machine is operated with a single penny.

In case more than one penny has been used, the additional pennies are discharged into the chute 39 and thus conveyed into the hopper 38. When it is desired to effect the discharge of another newspaper, it is merely necessary to turn the crank to the left to cause the engagement of the pin 22 by the slide bar 23, so as to bring the slots 11 and 14 into their upper positions.

When a newspaper has been discharged into the chute 4, the table 44 is brought into a position in which the newspaper upon the opposite side of the table is made to appear through the window 2, and the table is again in position to discharge the succeeding newspaper. As the newspapers are discharged from the table, the winding drums 130

57 and 60 are caused to take up the slack in the strings 63 so as to keep the strings taut upon the bundle of newspapers upon the table. It will be noted, however, that a varying quantity of string is released by the unwinding of the bundle of papers, according to the number of papers carried by the table. Because of the presence of the spring-pressed pin 55, however, meshing with the rack 56, and because of the proper proportioning of the sprocket wheels 45 and 47, the drums 57 and 60 are caused to take up all of the slack in the strings 63 when a maximum quantity of string is being released from the table 44, but the parts are so constructed, furthermore, that upon a less quantity of string being released, the spring-pressed pin 55 is permitted to slide over the rack 56, so as to keep the tension of the string 63 constant. When the last paper has been delivered through the chute 4, the knot 77 comes in contact with the lever 75, so as to cause, through the intervention of the various links and levers, the withdrawal of the coin guide 30 from its position above the chute 28 into a position in registry with the discharge chute 32. Should now, any further coins be inserted, the latter are conducted through the chute 32 around the operating mechanism into the pocket 33 upon the outside of the machine.

In order to re-load the machine, the crank 7 is turned toward the right until it contacts with one of the stops 36. In this position the cam groove 26 will have withdrawn the slide bar 23 beyond the path of movement of the pins 22. When now the lid 3 is raised, the spring 19 will be removed from the top of the pawl 17, and the weighted arm 18 will withdraw the pawl from coöperation with the notches 16. The sprocket wheel 13 is now free to rotate with the table 44 and the various sprocket chains. The raising of the lid 3 also causes the release of the beveled lug 70 from contact with the beveled surface 69 of the lever 67. As a result, the spring 67' causes the clutch members 50 and 51 to become disengaged. Simultaneously the raising of the lid causes the springs 81 to force the brake-shoes 82 into contact with the peripheries of the drums 57 and 60. The bundle of papers to be inserted into the machine is now placed upon the rods 83, and one after another the papers are placed upon opposite sides of the table 44, and the table gradually rotated until the entire bundle of papers has been inserted. During this operation the brakes 82 cause a constant tension to be placed upon the strings 63. The lid is now closed, and as a consequence, the brakes 82 are withdrawn from contact with the peripheries of the drums 57 and 60, and the clutch members 50 and 51 are caused to engage one another. The closing of the lid

3 also brings the spring 19 into contact with the pawl 17 so as to again force the latter into coöperation with the notches 16 upon the wheel 13. The coin guide 30 will also have been moved into registry with the chute 28 by the release of the lever 75. The parts are now in position to operate as before described.

In the modification shown in Figs. 8 to 12, when it is desired to insert a bundle of papers, the table 84 will be wound up at a central plant with a bundle of papers and the table and the attached papers will then be taken to the machine located at some public place. In order to insert the table 84 with its attached newspapers into the machine, the old table is first removed by releasing the catches 94 therefrom, and the table is withdrawn from the machine. In order to rapidly remove the strings from the drums 57 and 60, it is merely necessary to insert a knife into the recess 99, and cut the entire bundle of strings through the slots 98. The new table with its attached papers can now be inserted into the machine without delay. When the lid is now closed, the machine is again in condition to be operated for the discharge of newspapers.

While I have described my invention above in detail, I wish it to be understood that I am not necessarily limited thereby, but consider that my invention is a broad one and capable of many modifications and applications to different structures without departing from the spirit thereof.

I claim:

1. In a device of the character described, the combination of a rotary shaft, means for preventing a complete rotation of the shaft, 105 vending devices, means for conveying power from the shaft to the vending devices, means for coupling said last-mentioned means to the shaft, and means for permitting the free rotation of the power conveying means when the shaft is in a certain position.

2. In a device of the character described, the combination of vending devices, a rotary power-conveying mechanism for operating the same, and means for permitting the rotation of the power-conveying mechanism in either direction when the vending devices are being charged with articles, whereby the movement of the vending devices is unrestricted during the charging thereof.

3. In a device of the character described, the combination of a casing, a lid therefor, vending devices, a rotary power-conveying mechanism for operating the same, and means for permitting the rotation of the power-conveying mechanism in either direction when the lid is raised, whereby the movement of the vending devices is unrestricted during the charging thereof.

4. In a device of the character described,

the combination of a casing, a lid therefor, vending devices, and means for permitting the rotation of the power conveying means in either direction when the lid is raised, 5 comprising a releasable pawl.

5. In a device of the character described, a pivoted flat table, devices for retaining articles upon both sides thereof, comprising a cord wound around the same, means for 10 causing the discharge of one or more articles, and devices for taking up the cord as released to keep the same taut, comprising a spring-pressed pin and ratchet.

6. In a device of the character described, 15 a pivoted table adapted to support articles, and means permitting the removability of said table for charging purposes, comprising one or more pivoted blocks carrying spring-pressed pins.

20 7. In a device of the character described, a drum for receiving a cord having a slot in the same to permit the ready removability thereof by cutting.

8. In a device of the character described, 25 the combination of a casing, a lid therefor, a drum therein for receiving a cord, means for dispensing articles also in said casing, operative connections from said means for causing the cord to be wound upon the drum, 30 and a brake adapted to be thrown into operation against the drum when the lid is raised.

9. In a device of the character described,

the combination of a casing, a lid therefor, a drum therein for receiving a cord, means 35 for dispensing articles also in said casing, operative connections from said means for causing the cord to be wound upon the drum, including a clutch and means for causing the release of the clutch when the lid is 40 raised.

10. In a device of the character described, a thin support for sheets of printed matter, a cord wound around said support to retain 45 said printed matter thereon, said support and cord being adapted to retain the printed matter in position in a completely filled rectangular solid.

11. In a device of the character described, a support adapted to sustain two parallel 50 and oppositely-disposed piles of printed matter, a cord wound around said support and passing from one of the lower units of one of the piles directly to one of the lower units of the other pile, then directly over a 55 succeeding unit of the first mentioned pile, then directly over a similar unit of the other pile, and around the remaining units in a similar manner until both piles are retained in place.

In testimony that I claim the foregoing I have hereunto set my hand.

AMBROSE S. CARNELL.

Witnesses:

A. NEWCOMB,
ARTHUR WRIGHT.
